CENTERING APPARATUS FOR BOWLING
PIN HOLDERSJames J. McGinley, Williston Park, N. Y., assignor
to American Machine and Foundry Company, a
corporation of New Jersey

Application September 30, 1947, Serial No. 777,000

10 Claims. (Cl. 273—42)

1

This invention relates to bowling pin handling machines and more particularly to apparatus for centering the devices which engage and grip standing bowling pins to lift them above the alley during the sweeping operation and then replace them on the alley in the same positions they occupied before being gripped and lifted above the alley.

My invention relates to improvements in bowling pin resetting apparatus of the general type shown in U. S. Patent 2,217,709 granted October 15, 1940, to Gottfried J. Schmidt. Under adverse and extreme operating conditions it has been found that the cone shaped camming members sometimes have a tendency to cock when engaging with standing bowling pins. When this occurs there is a possibility that the pin causing the cocking might not be gripped or if gripped might not be reset in exactly the same position it occupied before being gripped and elevated. Cocking also might have a tendency to dent and damage the cone.

It is therefore an object of my invention to overcome this disadvantage by providing a simple device for centering bowling pin engaging and gripping devices over the normal on spot positions on an alley where pins are spotted prior to their engagement with standing bowling pins.

Another object of my invention is to provide a bowling pin gripper centering device for use with a combined setting and resetting table which rotates 180° when placing a new set of pins on an alley.

A further object of my invention is to provide a simple, reliable device for centering resetting devices over the openings in the support through which bowling pins pass to minimize the distance a horizontally movable pin gripping device travels when engaging with a standing bowling pin.

Another object is to provide a centering device which will not have any attachments connected to the bowling pin resetting units which could interfere with their being freely moved when brought into engagement with standing bowling pins.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

In the accompanying drawings:

2

Fig. 1 is a plan view of a bowling pin resetting apparatus with which my invention may be incorporated wherein parts of the mechanism have been broken away for clarity of illustration.

Fig. 2 is a side view of Fig. 1 taken along line 2—2.

Fig. 3 is a partial isometric view of the invention showing the centering device in operation.

In the drawings I have shown, for purposes of illustration, one embodiment of my invention wherein a bottom platform 10 is provided with a plurality of circular openings 12 which correspond in number and arrangement to a set of bowling pins positioned on a bowling alley. The top and bottom plates 10 and 14 are firmly held against the spacers 16 by means of nuts 18 which are screwed on bolts which pass through the spacers 16.

The pin setting holders 29 and resetting cones 20 which I have shown in Figs. 1, 2 and 3 may be similar in construction, design and operation to those shown in U. S. Patent 2,217,709 issued to Gottfried J. Schmidt on October 15, 1940. The pin setting holders 29 are fixedly mounted on the plate 31 and are actuated to hold bowling pins by suitable means such as suction as described in U. S. Patent 2,217,709. Each cone 20 is slidably mounted on the support 10 and has a rubber sealing ring 15 and a port 17. When a cone 20 has been centered over a standing pin, the head of the pin will close off the upper part of the cone from the atmosphere. The continued downward descent of the pin spotting table causes the cones 20 which have been cammed over the heads of standing bowling pins to be lifted off the lower platform 10 and continued downward movement of platform 14 brings the latter into contact with the rubber ring 15. Suction is then applied through tubes 37 and valves 39 and ports 17 to cause the standing bowling pins to be gripped and the cones 20 to be secured against movement by engaging with the bottom of platform 14.

For a further detailed description of how the bowling pin resetting devices 20 operate reference may be made if desired to the above mentioned U. S. Patent 2,217,709.

The table or plate 14 is supported by a shaft 24 on which brackets 22 fixedly connected to the plate 14, are rotatably mounted. One of the brackets 22 has a gear 21 by which the table may be rotated about the shaft 24 to bring a new set of bowling pins held by the spotter cups 55 29 to a position on the under side of the table

14 prior to being lowered onto the alley. A gear segment 23, pivotally mounted on a stud 19 carried by shoe 26, intermeshes with the teeth of gear 21 and causes the table 14 to rotate 180° to bring the pins held by the spotter cups 29 into position to be placed on the alley.

Actuating movement is imparted to the gear segment 23 by means of a cam actuated lever 25. The cam actuated lever 25 is pivotally connected to an actuating arm 27 which forms an integral part of gear segment 23. For further information respecting the mechanism for rotating the table 180° to place a new set of pins on the alley reference may be made to U. S. Patent 2,578,319 issued December 11, 1951, to Gottfried J. Schmidt.

The shaft 24 is fixedly mounted at either end in suitable shoes 26 which travel in guide channels 28. The guide shoes 26 are raised and lowered in a manner similar to that shown in U. S. Patent 2,217,709 referred to above, by means of cables 30.

In order to center the resetting cones 20, I have provided a centering plate 32 with circular openings 34 which are slightly larger than the circular openings 12 formed in table 10. Each circular opening 34 is preferably formed with a V-shaped notched section 36 which assists in centering the cones 20 over the openings 12. At the back end of centering plate 32, wire loops 33 have been employed in conjunction with the V-shaped notches 36 and operate in a manner similar to circular openings 34. Each wire loop 33 is secured to the plate 32 by suitable clamps 35.

The links 38 and 40, which support the centering plate 32 at either end, are pivotally connected at one end to brackets 42 attached to the top plate 14. The other ends of links 38 and 40 are pivotally attached to suitable brackets 44 carried by the centering plate 32.

Connecting links 46 which impart longitudinal movement to the centering plate 32 are connected at one end to links 40 and at the other end to lever arms 48. Swinging movement is imparted to lever arms 48 by the shaft 50 on which the lever arms 48 are fixedly mounted. The shaft 50, which is rotatably supported in bearing brackets 52 on table 14, also carries a lever arm 54 having a cam follower 56. The cam follower 56 is actuated by a cam 58 which is fixedly mounted on the shaft 24. One end of the lever arm 54 carries a finger 60 which is adapted to engage with a notch 62 formed in a link 64. The link 64 is pivotally connected to a bracket 68, by means of pin 66. Bracket 68 is fixedly mounted on the top plate 14.

A spring 70 is secured at one end to an anchor plate 72 carried by the top plate or platform 14 and at the other end to the link 54 so as to urge the cam follower 56 into engagement with the cam 58. Spring 70 also acts to hold the finger 60 locked in the notch 62 when these two members have been brought into engagement as a result of the turning of table or plate 14. When the table 14 descends to perform its resetting operation, the cam roller 74 mounted on the end of link 64, engages with a stationary cam 76 fixedly mounted on a guide 28 thereby disengaging the finger 60 from the notch 62.

The operation of my machine may be briefly described as follows:

After the second ball has been thrown suitable sweeping mechanism such as shown in U. S. Patent 2,250,503 granted July 29, 1941, to R. E. Rundell is usually employed in the type of pin handling machine to which I have referred for

removing the bowling pins and the bowling balls from the alley. Suitable mechanism (not shown) is also employed in this type of machine to place a bowling pin in each of the bowling pin holders 29.

In order to place a new set of pins held by the holders 29 on a bowling alley, the lever arm 25 is actuated causing the gear segment 23 to rotate the table 14 180° by engaging with the gear 21 which is fixedly connected to the table 14. When the table 14 rotates, in the direction indicated by the arrow shown in Fig. 2, the cam roller 56 rides on the stationary cam 58.

When the table 14 has rotated approximately 90° the cam roller 56 will have engaged with the high portion of cam 58. This will cause the lever arms 48 to pull the connecting links 46 in the direction indicated by the arrow in Fig. 2. This in turn causes the centering plate 32 to be pulled longitudinally with respect to the bottom plate 10 until the V-shaped notches 36 reach predetermined points where the bowling pin gripper devices 20 will be centered over the holes 12 when they engage with the respective notches 36.

The centering plate 32 is caused to be locked in this centering position by finger 60 engaging with the notch 62 of pivoted arm 64. Friction and the action of spring 70 on the lever arm 54 cause finger 60 and the notch 62 to remain in engagement thereby causing the centering member 32 to be locked against further movement until the finger 60 is disengaged from the notch 62.

At approximately the same time, the pin gripping respotting units 20 will, under the force of gravity, slide downwardly until they are stopped by the V-shaped notch 36 formed in the openings 34 of the centering plate 32.

When the table 14 has rotated 180° under the actuation of the gear segment 23, in the direction indicated in Fig. 2, the spotting cups 29 will be on the underside of table 14, and the bowling pin resetting grippers 20 will be on the upper side of table 14.

As the table 14 has completed its 180° rotation it is locked against further rotation by suitable means (not shown) and then lowered by means of cables 30 to allow the holders 29 to release and spot a new set of bowling pins on a bowling alley in proper playing arrangement. It should be noted that when the table 14 is lowered to spot a new set of pins on a bowling alley the cam roller 74 will travel downwardly with the table 14 on that side of the guide channel 28 which is spaced from the cam 76.

When the table 14 reaches its lowermost point of travel the pins are released on the alley and the table 14 is then elevated by the cables 30. When the table 14 reaches its upper limit of travel the actuating arm 25 is moved in the opposite direction thereby causing the gear segment 23 to rotate the table 14 180° back to its starting position.

After a player has thrown his first ball, the table 14 is lowered by means of cables 30 down towards the bowling alley. As the table 14 travels downwardly, the cam roller 74 engages with the stationary cam 76 causing the notch 62 to be pulled away from the finger 60. The spring 70 then by pulling on arm 54 causes the cam roller 56 to be brought into engagement with the lower portion of cam 58. This in turn causes the centering plate 32 to swing forward out of engagement with the centered respotting devices 20 through links 38, 40, 46 and 48.

As the table 14 approaches its lowermost point of travel the heads of any standing bowling pins will pass upwardly through the openings 12 of the bottom plate 10 and come into engagement with the tapered camming and gripping devices 20. As the camming and gripping devices 20 engage with the heads of the standing bowling pins they are caused to shift laterally until they become centered over the standing bowling pins which may have been moved from their original position by the first ball. Continued downward movement of table 14 causes the standing pins to lift the cone shaped members 20 with which they engage above the plate 10 thereby bringing the rubber rings 15 into engagement with the top plate or platform 14. Suction or other suitable gripping means are then employed to cause the standing pins to be gripped and locked against movement with respect to the platform 14.

In the machine with which the present invention has been shown for purposes of illustration, suction is applied through tubes 37, valves 39 and orifices 17 to effect a gripping action on the standing bowling pins. For a further detailed description of this operation reference may be made to the aforementioned U. S. Patent 2,217,709.

The table 14 is then raised by means of cables 30, lifting the gripped standing bowling pins above the alley to allow the fallen pins and bowling ball to be removed from the bowling alley in the manner mentioned hereinbefore. Table 14 is then lowered again to allow the pin gripping devices 20 to replace their respective gripped pins on the alley in the same position they occupied before being engaged and gripped by these devices. After the gripped standing pins have been replaced on the alley, and the gripping devices 20 have been released, table 14 is again elevated above the alley to allow the player to throw his second ball.

It will therefore be seen that I have provided a simple device for centering the bowling pin resetting members 20 over the positions on a bowling alley on which bowling pins are spotted. The centering device 32 that I have described makes use of the normal movements of the table 14 and does not attach any encumbrances on the cone 20 which will interfere with its ability to slide when engaging with the head of a standing bowling pin, or which will add any weight to the cones 20. In other words the cone gripping devices 20 are just as free to shift laterally as they are when no centering device is employed with these cones.

My centering device also has the advantage that it engages with the center part of each cone member instead of the top or bottom thereby causing less strain and wear to be exerted on the cones 20 when the table 14 undergoes its 180° rotation.

It will also be noted that my centering device minimizes the tendency of the cone 20 to cock or become jammed when it engages with a bowling pin under adverse or extreme operating conditions due to the fact that it will never have to travel between two extreme locations as might happen if the cones 20 were not centered before being brought into engagement with the standing pins.

The invention above described may be varied in construction within the scope of the claims, for the particular device selected to illustrate the invention is but one of many possible embodiments of the same. The invention, therefore, is not to

be restricted to the precise details of the structure shown and described.

What is claimed is:

1. In a bowling pin handling apparatus of the type employing a turning table for setting and resetting bowling pins on a bowling alley, apparatus for turning said table 180° when spotting a new set of bowling pins on a bowling alley, freely slideable camming devices having pin grippers positioned over openings formed in said turning table, a plurality of interconnected confining members surrounding said camming devices for limiting the extent of sliding movement of each device, mechanism for adjusting said members to further limit the extent of free sliding movement of said devices in one direction under the action of gravity when the table is turning so as to center said devices with respect to the openings formed in said turning table, and mechanism for returning said confining members to normal position when said table travels vertically to allow said devices to move freely in all directions when engaging with standing bowling pins.

2. In a bowling pin handling apparatus of the type employing a turning table which rotates on a horizontal axis for setting and resetting bowling pins on a bowling alley; freely shiftable pin gripper devices positioned over holes formed in said table corresponding in number and arrangement to the positions on a bowling alley on which bowling pins are spotted; a centering device, having openings with a V shape at one end, associated with said table for centering said bowling pin gripping devices over said holes by means of said pin grippers engaging with said V-shaped ends each time the table is turned; mechanism for moving said centering device relative to said table to bring said V-shaped ends into and out of operative centering position; and mechanism for lowering and raising said table to grip, lift and replace standing bowling pins on a bowling alley.

3. In a bowling pin handling apparatus of the type employing a turning table for setting and resetting bowling pins on a bowling alley, freely slideable camming devices having pin grippers positioned over openings formed in said turning table, centering devices surrounding each of said slideable camming devices, mechanism for moving said centering devices with respect to said table to bring the centering devices to a position where they will engage with said camming devices when the camming devices are properly centered with respect to said openings, apparatus for turning said table to cause said camming devices to slide into contact with said centering devices, and mechanism for moving said centering devices out of contact with said camming devices after each camming device has been centered.

4. In a bowling pin handling device having apparatus for supporting a plurality of pin gripper locating devices, a centering device for centering said gripper locating devices with respect to the positions on a bowling alley on which bowling pins are spotted prior to each gripping operation comprising, a member having a plurality of circular openings corresponding to the positions on a bowling alley on which bowling pins are spotted, said openings having a V-shaped notch for locating said devices when said devices are moved into contact therewith, apparatus for causing said pin gripper locating devices to move into contact with said V-shaped notches, and mechanism for moving said member longitudi-

nally to center said gripper locating devices over each position on a bowling alley on which bowling pins are spotted.

5. In a bowling pin handling device of the type employing a platform having mechanism for setting a new set of pins on the alley mounted on one side of the platform and pin gripping devices for resetting standing bowling pins on a bowling alley mounted on the other side of the platform, a device for centering said pin gripping devices over the positions on a bowling alley on which bowling pins are spotted, comprising a plate having a plurality of openings through which said pin gripping devices extend, said openings having a V-shaped portion for locating a pin gripping device in said opening, and a mounting for moving said plate longitudinally with respect to said platform to cause the V-shaped portion to positively locate each pin gripping device over the positions on a bowling alley over which bowling pins are spotted.

6. Apparatus for engaging, gripping, lifting and replacing standing bowling pins on a bowling alley comprising, a support, a plurality of pin gripping devices slidably mounted on said support, mechanism for tilting said support to cause said pin gripping devices to slide with respect to the support under the action of gravity, a limiting device associated with said support for limiting the extent each pin gripping device slides on said support to position said devices on the support so that they will be centered over the pin spot positions on a bowling alley when the support is in horizontal position, and mechanism for moving said limiting device out of engagement with said pin gripping devices after said support has been returned to its original horizontal position.

7. Apparatus for engaging, gripping, lifting and replacing standing bowling pins on a bowling alley comprising, a support, pin gripping devices fixedly mounted on one side of said support, pin gripping devices slidably mounted on the other side of said support, mechanism for alternately turning said support to place a new set of pins on an alley by means of said fixedly mounted pin gripping devices, and to grip, elevate and replace standing bowling pins on said alley by means of said slidably mounted pin gripping devices, a member for limiting the movement of said slidably mounted pin gripping devices each time said support is turned to place a new set of pins on the alley so as to position said devices on the support so that they will be centered over the pin spot positions on the bowling alley when the support is in horizontal position, mechanism for locking said member in position with respect to said support each time said table is turned, and means for releasing and moving said member out of engagement with said slidably mounted pin gripping devices each time said slidably mounted pin gripping devices are brought into operation to grip, elevate and replace standing bowling pins on said bowling alley.

8. In a bowling pin handling device having, pin gripper locating devices, apparatus for supporting said pin gripper locating devices, a centering device for centering said pin gripper locat-

ing devices with respect to the positions on bowling alleys on which bowling pins are spotted prior to each gripping operation comprising, a member having a plurality of openings corresponding to the positions on a bowling alley on which bowling pins are spotted, guides for confining said member to reciprocatory movement relative to said apparatus, mechanism for moving said member longitudinally to position said openings so that when the locating devices are brought into engagement with corresponding parts of said respective openings, said devices will be correctly centered, means for causing the locating devices to engage said corresponding parts of the openings in said member, and means for returning said member to its original position.

9. Apparatus for handling bowling pins comprising, a platform, pin gripping members slidably supported on said platform, said pin gripping members having pin contacting surfaces for centering said pin gripping members over standing bowling pins upon engagement therewith, a unitary mechanism having individual contacting surfaces adapted to engage with each of said members to center the pin gripping members on said platform over the positions on a bowling alley on which bowling pins are spotted, apparatus for moving said platform towards and away from that area of a bowling alley where pins are positioned to bring said pin gripping members into engagement with standing bowling pins, and means to position the contacting surfaces of said centering mechanism so that when the pin gripping members are brought into engagement with the contacting surfaces, said members will be correctly centered prior to said members being brought into engagement with standing bowling pins, means for causing the pin gripping members to engage said contacting surfaces, and means for returning said contacting surfaces to their original position.

10. In a machine for setting and resetting bowling pins on a bowling alley, a platform having a plurality of circular openings formed therein, mechanism for moving said platform towards and away from a bowling alley, freely shiftable pin-engaging and gripping devices positioned over each of said openings, interconnected guiding members having surfaces for individually engaging with each of said devices, and means to position said surfaces of said interconnected guiding members so that when the pin engaging and gripping devices are brought into engagement with said surfaces of said interconnected guiding members, said devices will be correctly centered prior to said devices engaging with standing bowling pins, means for causing the pin engaging and gripping devices to engage the said surfaces, and means for returning said surfaces to their original position.

JAMES J. McGINLEY.
